UNITED STATES PATENT OFFICE.

OTTIELEE FIELDS, OF KANSAS CITY, MISSOURI.

DESIGN FOR A TOWEL HANGER AND MARKER.

56,963.

Specification for Design.

Patented Jan. 25, 1921.

Application filed August 7, 1920. Serial No. 402,019. Term of patent 3½ years.

To all whom it may concern:

Be it known that I, OTTIELEE FIELDS, a citizen of the United States, residing at Kansas City, in the county of Jackson and State of Missouri, have invented a new, original, and ornamental Design for a Towel Hanger and Marker, of which the following is a specification, reference being had to the accompanying drawing, forming a part thereof.

In the drawing—

The figure shown represents a perspective view of a device embodying my improved design.

The face portion of the device embodying my design comprises a plate with a beaded border and of approximately rectangular outline with the upper part thereof slightly widened, this upper part being provided with an oblong tablet connected by branch beads with the lower corners of the plate.

I claim:

The ornamental design for a towel hanger and marker, as shown.
